UNITED STATES PATENT OFFICE.

FRANK J. KAUFMANN AND WILLIAM N. MARSDEN, OF AMSTERDAM, NEW YORK, AS-SIGNORS TO FOWNES BROTHERS AND COMPANY, OF LONDON, ENGLAND, A FIRM COMPOSED OF WILLIAM GARDNER RIGDEN, WILLIAM FOWNES RIGDEN, EDWARD FOWNES RIGDEN, STANLEY FOWNES RIGDEN, SAMUEL J. URWICK, AND HENRY URWICK.

THREAD-DRAWING AND THREAD-CUTTING MECHANISM FOR SEWING-MACHINES.

1,137,143.

Specification of Letters Patent. Patented Apr. 27, 1915.

Application filed December 7, 1912. Serial No. 735,371.

To all whom it may concern:

Be it known that we, FRANK J. KAUFMANN and WILLIAM N. MARSDEN, citizens of the United States of America, residing in 5 Amsterdam, county of Montgomery, and State of New York, have invented a certain new and useful Improvement in Thread-Drawing and Thread-Cutting Mechanisms for Sewing-Machines, of which the following is a specification.

This invention relates to thread drawing and thread cutting mechanisms for sewing machines, and has for its object a means to economize time in forming the seams, to 15 materially eliminate defective work and to effect substantial and desirable economy in the amount of the delicate and expensive silk threads commonly used for ornamentally stitching gloves or other articles.

As regards the seam stitching mechanism the invention relates more particularly to that kind of sewing machine, usually equipped with a plurality of needles, employed extensively in the manufacture of 20 gloves. In glove making, the back of the glove is ornamented by a plurality of longitudinal lines of broad stitching, technically known as "Brosser" point; and the sewing machines within this invention are those 25 employed for running one or more lines of stitching known as "Harris" or "Imperial" point along each side of the line of "Brosser" point. Such "Harris" or "Imperial" point stitching should have at the 30 beginning and termination thereof a sufficient length of free thread to permit of 35 the ends being passed through to the inside and tied or otherwise secured.

In machines equipped with the structural features of my invention, and operating 40 according to that invention, there is provided a suitable means whereby the operator may cause a definite extent of slack in the thread between the needle and the spool, 45 when a stitching operation has been completed. A gage is provided adjacent the needle whereby a point may be indicated according to which the slack, after it has 50 been drawn through the needle, may be severed so as to leave just the length necessary to fasten the finished seam and to begin

a new one. When the stitching is completed, the slack having been exactly determined and supplied, the presser foot must be raised and loops afforded by the slack 55 thread may be drawn away from the needles. The gage indicates to the operator just where the loops should be cut so that there shall be left at the ends of the lines of stitching on the article sufficient free 60 lengths of thread and in the needles free 65 lengths of thread of sufficient length to provide for the slight take-up that occurs when a new stitching operation is commenced and leave attached to the next sewn article or 70 glove blank a required extent of free thread at the beginning of the lines of stitching. The gage may be, and preferably is, not only a gage but also a cutter so that when an instrument of suitable width is passed 75 under the presser foot when a line of stitching has been completed, loops are thus formed and may be carried away from the presser foot, and the two sides of the loops will be sufficiently separated to permit of 80 one of the sides of each loop being severed by pressing them against the cutting edge of the gage.

In the accompanying drawing: Figure 1, is a front elevation indicating a double 80 needle machine equipped according to this invention; Fig. 2, an elevation of the left hand side thereof; Figs. 3, 4 and 5 are respectively a front elevation, a plan view and side elevation illustrating the manner of 85 gaging and cutting the thread loop; and Fig. 6 a view showing a suitable tool for handling the thread loop.

The special means shown for providing the required amount of slack thread comprises an arm 1 hinged on the front part of the head at 2 and having at its upper free end a loop 3 through which the threads pass. The arm has a reaction spring 5 that tends to hold it in uppermost position and its 90 downward movement is limited by an adjustable stop 6 so that when a stitching operation is completed and the slack thread required, the operator simply presses down the arm to draw from the spools or bobbins 95 the required amount of slack and when released the arm may return automatically 100

to normal position. Any means, however, by which the operator may draw the required amount of slack thread may be adopted. Such a means might be, for instance, an adjustable stop 7 (shown in dotted lines Fig. 1) located on the base of a head and under the path of the thread. The operator may then place her fore finger on the arm and press it down until it is arrested by the stop. The gage is shown as a plate 8 mounted upon a bracket on the head of the machine just above the bed plate and in rear of the presser foot. The upper edge 8' of the gage is fashioned to a sharp knife edge. Fig. 6 indicates a suitable tool having a broad flat body 9, a hooked end 10 and a notch 11 in the rear edge of the flat body. When the stitching operation is completed and after the arm 1, is depressed to provide a measured thread slackness and the presser foot is raised the two loops X one for each of the two needles shown, are carried rearwardly over the gage by the flatwise held tool body 9, as easily permitted by the thread slackness and without imminent danger of breaking the delicate threads, the lateral length of the drawn loops being limited or measured by the extent of slackness previously given the threads by depressing the arm 1, to the stop 6, or 7. When the thread loops are drawn rearwardly, the tool may be turned edgewise as seen in Figs. 4 and 5 and the threads seated in the tool notch 11. The upper and lower branches of the loops are then sufficiently far separated to permit of the lower branches 12 being cut by pressing them against the cutter, thus leaving attached to the article lengths of thread 12 and to the needles somewhat greater lengths of thread 13. When the next sewing operation is commenced some parts of the lengths of thread attached to the needles will be taken up by the first few stitches.

By our invention the thread may be steadily drawn through the tension devices to a predetermined measured extent of slackness by an easily controlled manual depression of the arm 1, to its stop, and with little or no danger of breaking a delicate thread, and the thread loop or loops are laterally drawn with little friction only, through the needle by the manually operated tool and to the full extent of the slackness previously and definitely measured by operation of the stop-limited manually actuated arm 1, whereby there is ample non-wasteful length of severed thread left in the needle or needles of our machine to assure safe starting of the next sewing operation without requiring time-consuming hand-pulling of the severed thread end through the needle. In prior machines there is no tool or device whereby the thread is drawn through the needle to the full ex-

tent of a predetermined measured previously given slackness and independently of release of the fabric from its holding and feeding devices, as in our invention, and after the laterally positioned thread is severed by the cutter of said prior machine, insufficient thread remains in its needle and the operator must sacrifice time in drawing the thread through the needle before the next sewing operation can safely be started. This operation is also apt to waste thread.

As regards the herein-described and claimed improvements in the art of producing machine stitched fabric seams, it is not essential that the thread loops be severed at a definitely indicated place, or that the projecting thread ends be passed inwardly through the fabric so as to be invisible at the outer face thereof, or that the inwardly passed thread ends of two rows of stitches shall be tied together at the inner face of the work, but in practicing the invention for the special purpose above named of ornamenting the backs of gloves, it is desirable to use all these operative steps or features of our invention.

We claim:

1. A sewing machine having a manually operative pivoted arm located between the spool and the head of the machine through an opening in the free end of which arm the thread passes, means tending to hold the arm in an elevated position, and means for limiting depression of the arm whereby a definite amount of slack thread is provided by actuation of the arm and independently of release of a sewn fabric from its holding or feeding devices, and a gage for determining the point at which the thread is to be severed.

2. A sewing machine having a manually operated pivoted arm located between the spool and the head of the machine through an opening in the free end of which arm the thread passes, means tending to hold the arm in an elevated position, and means for limiting depression of the arm whereby a definite amount of slack thread is provided by actuation of the arm and independently of release of a sewn fabric from its holding or feeding devices, and a fixed gage located adjacent the presser foot of the machine and comprising a plate having a cutting edge indicating where a laterally drawn thread loop shall be cut at the termination of a stitching operation, substantially as described.

3. A sewing machine having a spindle for a spool, a reciprocating needle, an arm located between the spindle and the needle, said arm being pivoted on the front part of the head and extending rearwardly and upwardly, and having a loop in its free end through which the thread may pass, a spring for holding said arm raised, and an ad-

justable stop on the base of the head within reach of the pivoted arm, substantially as described.

4. A sewing machine having a spindle for a spool, a reciprocating needle, an arm located between the spindle and the needle, said arm being pivoted on the front part of the head and extending rearwardly and upwardly, and having a loop in its free end 5 through which the thread may pass, a spring for holding said arm raised, an adjustable stop on the base of the machine within reach of the pivoted arm, a bracket on the machine, and a gage mounted in said bracket 10 just above the bed plate and in rear of the presser foot, substantially as described.

5. A sewing machine having a spool spindle, a reciprocating needle, a pivoted rearwardly extending arm between the spindle 20 and the needle, an opening in the free end of said arm, means for yieldingly holding said arm in raised position, a stop against which said arm may strike when swung downward, and a gage arranged in proper 25 relation to the stop and the needle for determining the point at which the thread is to be severed, substantially as described.

6. A sewing machine having a spool spindle, a reciprocating needle, a pivoted rearwardly extending arm between the spindle 30 and the needle, an opening in the free end of said arm, means for yieldingly holding said arm in raised position, a stop against which said arm may strike when swung 35 downward, and a gage knife with its edge upturned secured to the head of the machine in proper relation to the stop and the needle, substantially as described.

7. A sewing machine having a spool spindle, a reciprocating needle, a vertically movable, thread-engaging means between the spindle and the needle, and means to limit the movement of said thread-engaging means, the lower of such limiting means be-

ing an adjustable stop secured to the base of 45 the machine, substantially as described.

8. A sewing machine having a spool spindle, a reciprocating needle, a vertically movable, thread-engaging means between the spindle and the needle, means to limit the 50 movement of said thread-engaging means, the lower of such limiting means being an adjustable stop secured to the base of the machine, and a thread cutting gage arranged for determining the point at which 55 the thread is to be severed, substantially as described.

9. A multiple needle sewing machine having means for supporting spools, needles, a spring-held swinging arm pivoted to the 60 head, an opening in said arm through which threads may pass, a stop against which said arm may strike when swung downward, and a cutting gage in the rear of the needles 65 for determining the point at which the thread is to be severed, substantially as described.

10. A sewing machine having a spool spindle, a reciprocating needle, a pivoted rearwardly extending arm between the spindle 70 and the needle, an opening in the free end of said arm, means for yieldingly holding said arm in raised position, a stop against which said arm may strike when swung downward, a gage knife arranged in 75 proper relation to the stop and the needle, and a flat bladed tool having a suitable notch, whereby the thread loop formed by the descent of said arm may have one of its members brought into engagement with the 80 gage knife, substantially as described.

In testimony whereof, we have hereunto subscribed our names.

FRANK J. KAUFMANN.
WILLIAM N. MARSDEN.
